US00D760270S

(12) **United States Design Patent**
Herold et al.

(10) **Patent No.:** **US D760,270 S**
(45) **Date of Patent:** **** Jun. 28, 2016**

(54) **DISPLAY SCREEN WITH GRAPHICAL USER INTERFACE**

(71) Applicant: **Microsoft Corporation**, Redmond, WA (US)

(72) Inventors: **Jeffrey Alan Herold**, Kirkland, WA (US); **Nicholas R. Barling**, Redmond, WA (US); **Charla Pereira**, Seattle, WA (US); **Arianne Taylor**, Woodinville, WA (US)

(73) Assignee: **Microsoft Corporation**, Redmond, WA (US)

(**) Term: **14 Years**

(21) Appl. No.: **29/478,880**

(22) Filed: **Jan. 9, 2014**

(51) LOC (10) Cl. **14-04**

(52) U.S. Cl.

USPC **D14/487**

(58) **Field of Classification Search**

USPC D14/485-495

CPC G06T 13/80; G06T 15/02; H04N 1/00424; G06F 3/04817; G06F 3/0481

(57) **CLAIM**

The ornamental design for a display screen with graphical user interface, as shown and described.

DESCRIPTION

FIG. 1 is a front view of a display screen with graphical user interface showing our new design;

FIG. 2 is a front view of the display screen with graphical user interface showing an alternative embodiment of our new design; and,

FIG. 3 is a front view of the display screen with graphical user interface showing an alternative embodiment of our new design.

The broken line showing of the remainder of the user interface and the remainder of the display screen is for environmental purposes only and forms no part of the claimed design.

1 Claim, 3 Drawing Sheets
